ELECTRIC HORN

Joe White, Anderson, Ind., assignor to General
Motors Corporation, Detroit, Mich., a corpora-
tion of Delaware

Application October 20, 1941, Serial No. 415,688

3 Claims. (Cl. 177—7)

This invention relates to electric horns comprising a flexible diaphragm having its peripheral edge clamped between a base and a projector or trumpet. The diaphragm is operated by an electromagnetic motor comprising a core supporting a winding, and an armature connected with the diaphragm by a rod extending thru an opening in the core and base. In order to adjust the air gap thru the armature and core it has been the practice to provide for adjustably mounting the magnet core upon the base.

It is an object of the invention to reduce the cost of manufacture of horns of this type. In order to accomplish this I directly attach the magnet core to the base, for example by electric welding, and I provide for deforming the base at a plurality of places between the magnet core and the periphery of the base. By changing the shape of the base at different points by pressing it toward the diaphragm or pulling it away from the diaphragm I am able to obtain an air gap between the armature and core which is substantially uniform for all practical purposes. By eliminating a separate means for adjustably mounting the core upon the base I am able to effect a material reduction in cost.

Further objects and advantages of the present invention will be apparent from the following description, reference being had to the accompanying drawing wherein a preferred embodiment of the present invention is clearly shown.

In the drawing:

Fig. 1 is a plan view of an electric horn embodying the present invention.

Fig. 2 is a sectional view taken on the line 2—2 of Fig. 1.

Fig. 3 is a sectional view taken on the line 3—3 of Fig. 2.

Fig. 4 is a fragmentary view on a large scale showing the use of a tool for deforming the base of the horn.

Fig. 5 is a sectional view on line 5—5 of Fig. 4.

The horn comprises a diaphragm 20 having its peripheral edge clamped by bolts 21 between a horn trumpet or projector 22 and the flange 23 of a base 24. Upon the central portion of base 24 a magnet core 25 is secured by electric welding as indicated at 26. A bracket 27 having feet 28 electrically welded to the base 24 supports armature spring 29, a contact spring 30 and a contact bracket 31 which is insulated. Spring 30 carries a contact 32 for engaging a stationary contact 33 attached to bracket 31.

Diaphragm 20 is centrally apertured to receive the lower end 35 of a rod 36. Rod 36 provides a

shoulder 37 for receiving a washer 38. The part 35 extends thru washer 38, washer 39, the diaphragm 20 and a stiffening washer 40, then is riveted over at 41 to secure the parts 38, 39, 20 and 40 to the rod 36. The rod 36 has a reduced upper end 42 which passes thru an armature 43. A washer 44 having a flange 45 is fitted against the squared right hand end of armature spring 29. The flange 45 also engages the flat end of a bracket 46 having an upper end portion 47 apertured at 48 to receive the contact spring 30. The upper end of the part 42 is riveted at 49 to clamp the bracket 46, spring 29, the washer 44 and the armature 43 against a shoulder 50 of the rod 36. The portion 47 of bracket 46 is bendable in order to adjust the spacing of the contacts 32 and 33 when the armature 43 is in its lowest position or nearest to the core 25.

The core 25 supports a magnet coil 51 having one end 52 connected with a terminal, not shown, and another end 53 connected with an extension 31a of bracket 31. Part 31a is connected by wire 54 with a resistance 55 mounted on an insulating plate 56 in turn mounted on a metal bracket 57 attached to base 24 by rivets 58 integral with the base. Contact 32 is grounded thru the spring 30 and the bracket 27 and base 24. One end of the resistance 55 is grounded on the base 24. This places the resistance 55 in shunt with the contacts 33 and 32 in order to reduce sparking.

The magnet coil 51 is secured by clips 60 integral with base 24 and formed by partially shearing away portions of the base thus leaving apertures 61 extending a substantial distance diametrically across the base between the flange 23 thereof and the central portion 62 (Fig. 3) which receives the core 25. Thus apertures 61 tend to make the base 24 more readily deformable. For purposes of changing the shape of the base 24 in order to adjust the air gap between armature 43 and core 25, the base is provided with four holes 63 arranged symmetrically with respect to the apertures 61. As shown in Fig. 4 on an enlarged scale each hole 63 is adapted to receive the head 64 of a tool 65. Head 64 is connected with the main portion of the tool by a shank 66 eccentric with respect to the head 64 so as to provide a shoulder 67 for engaging the under side of the base 24, in order that the base may be pulled upwardly, that is, away from the diaphragm 20 when such adjustment is required in order to shorten that portion of the air gap which is closest to that particular hole 63 into which the tool 65 is inserted. When it is desired to lengthen the air gap the under side of the base 24 is en-

gaged by shoulder 63 of the tool 65. The tool 65 may be operated in a vertical direction or at right angles to the base 24 by any suitable means such as hydraulic pressure. The tool 65 is of course movable laterally in order that the head 64 may be hooked under some portion of the base 24. With the complete horn assembly as shown mounted upon a suitable fixture the attendant inspects the air gap by the use of shims or spacers of known thickness. If, for example the upper left hand portion of the air gap as viewed in Fig. 1, is found to be too short, the tool 65 is inserted in the upper left hand hole 63 and is caused to exert pressure downwardly upon the base in order to move the base downwardly with respect to the upper left hand portion of the armature 43. The pressure applied to the tool 65 is such to move the base 24 downwardly in order to correct the deficiency of the air gap. If the air gap of this part had been too long then the head 64 of the tool 65 would be hooked under the side of the base 24 and the tool would be pulled upwardly in order to shorten the air gap.

While the embodiment of the present invention as herein disclosed, constitutes a preferred form, it is to be understood that other forms might be adopted, all coming within the scope of the claims which follow.

What is claimed is as follows:

1. An electric horn having a sheet metal base provided with a central portion raised above a peripheral flange, a diaphragm secured to the flange, an electromagnet core attached to the central portion of the base and having pole faces spaced from the base, a magnet coil supported by the core, a rod extending through the core and base and attached at one end to the diaphragm, a spring member supported by the base and attached to the other end of the rod, an armature attached to the rod between the spring member and the core and extending over the pole faces of the core, and means for adjusting the gap between the armature and pole faces while the parts specified remain assembled, said means being provided by deformable portions of the base between the peripheral flange and the central portion to which the core is attached and located on opposite sides of the elongated openings of the base, said portions being deformed toward the diaphragm by pressure applied upon the outer surface of the base, and each of said portions being apertured to receive a tool to be passed therethrough and to be hooked under the base to deform it away from the diaphragm.

2. An electric horn having a sheet metal base provided with a central portion raised above a peripheral flange, a diaphragm secured to the flange, an electromagnet core attached to the central portion of the base and having pole faces spaced from the base, a magnet coil supported by the core, a rod extending through the core and base and attached at one end to the diaphragm, a spring member supported by the base and attached to the other end of the rod, an armature attached to the rod between the spring member and the core, and extending over the pole faces of the core, means for securing the coil to the core and comprising parts of the base partially sheared away leaving elongated openings in said base symmetrically disposed with respect to the core and on opposite sides thereof, and means for adjusting the gap between the armature and pole faces while the parts specified remain assembled, said means being provided by deformable portions of the base between the peripheral flange and the central portion to which the core is attached and located on opposite sides of the elongated openings of the base, said portions being deformed toward the diaphragm by pressure applied upon the outer surface of the base, and each of said portions being apertured to receive a tool to be passed therethrough and to be hooked under the base to deform it away from the diaphragm.

3. An electric horn comprising a sheet metal base, a diaphragm located on one side of the base and connected therewith, an electromagnet core attached to the other side of the base and having pole faces spaced from the base, a magnet coil associated with the core, an armature extending over one of the pole faces of the core and connected with the diaphragm, and means for adjusting the gap between the armature and pole faces while the parts specified remain assembled, said means being provided by deformable portions of the base located around the portion of the base to which the core is attached, said portions being deformed toward the diaphragm by pressure applied upon the outer surface of the base, and each of said portions being apertured to receive a tool to be passed therethrough and to be hooked under the base to deform it away from the diaphragm.

JOE WHITE.
